UNITED STATES PATENT OFFICE

166,829

MEAT COOKING PAN

Walter J. Sherman, Muscatine, Iowa

Application November 27, 1951, Serial No. 17,530

Term of patent 14 years

(Cl. D44—8)

To all whom it may concern:

Be it known that I, Walter J. Sherman, a citizen of the United States, residing at Muscatine, county of Muscatine, State of Iowa, have invented a new, original, and ornamental Design for a Meat Cooking Pan, of which the following is a specification, reference being had to the accompanying drawing, forming a part thereof.

In the drawing:

Figure 1 is a perspective view of a meat cooking pan showing my new design.

Fig. 2 is a longitudinal vertical sectional view on the line 2—2 of Fig. 1.

Fig. 3 is an end elevational view thereof.

I claim:

The ornamental design for a meat cooking pan, substantially as shown.

WALTER J. SHERMAN.
